(57) **CLAIM**

The ornamental design for a knife handle, as shown and described.

DESCRIPTION

FIG. 1 is a left side elevational view of the knife handle illustrating its relation to a first type of knife blade, the right side being substantially identical;

FIG. 2 is a top plan view of the knife handle;

FIG. 3 is a bottom plan view of the knife handle;

FIG. 4 is a front elevational view of the knife handle;

FIG. 5 is a rear elevational view of the knife handle; and, FIG. 6 is a left side elevational view of the knife handle illustrating its relation to a second type of knife blade.

The broken line illustrations in the drawing figures are

intended to illustrate the environment of the design sought to

be patented and form no part of the design.
